UNITED STATES PATENT OFFICE

153,565

DESIGN FOR AN OUTDOOR TRASH BURNER

Tyree V. Tankersley, Wichita, Kans.

Application August 16, 1947, Serial No. 140,911

Term of patent 14 years

(Cl. D81—1)

To all whom it may concern:

Be it known that I, Tyree V. Tankersley, a citizen of the United States, residing at Wichita, in the county of Sedgwick and State of Kansas, have invented a new, original, and ornamental Design for an Outdoor Trash Burner, of which the following is a specification, reference being had to the accompanying drawing, forming part thereof.

Fig. 1 is a side view of an outdoor trash burner, showing my new design, the opposite side being similar.

Fig. 2 is a front view;

Fig. 3 is a back view, and

Fig. 4 is a top plan view thereof.

I claim:

The ornamental design for an outdoor trash burner, substantially as shown and described.

TYREE V. TANKERSLEY.
